UNITED STATES PATENT OFFICE.

MAX COHN, OF CHICAGO, ILLINOIS.

TOILET ACCESSORY.

1,370,950.

Specification of Letters Patent.

Patented Mar. 8, 1921.

Application filed March 8, 1920. Serial No. 364,172.

To all whom it may concern:

Be it known that I, MAX COHN, a citizen of the United States, and a resident of the city of Chicago, in the county of Cook and State of Illinois, have invented certain new and useful Improvements in Toilet Accessories; and I do hereby declare that the following is a full, clear, and exact description of the same, reference being had to the accompanying drawings, and to the numerals of reference marked thereon, which form a part of this specification.

Novelty articles, such as dolls and the like, are very often put in the commercial market and sold extensively to be used merely as articles of ornamentation having no particular usefulness.

This invention relates to an ornamental novelty article in the form of a hollow kewpie bathing girl adapted to be filled with face powder and having apertures in the head thereof to permit the powder to be shaken therefrom onto a chamois skin which forms the lining of a removable cap for the doll.

It is an object of this invention to provide an ornamental article constructed to be adaptable for practicable purposes.

It is also an object of the invention to provide a novelty toilet article constructed to serve a practicable as well as an ornamental purpose and having a removable powder puff or chamois skin forming a part thereof.

Another object of the invention is to provide a hollow kewpie doll the head of which is perforated and covered by a removable cap adapted to normally cover the head perforations and useful as a powdering cloth when removed from the doll's head.

It is an important object of this invention to provide an ornamental novelty article in the form of a kewpie bathing girl which is adapted to be used as a face powder container and also adapted to provide a means for applying the powder carried thereby.

Other and further important objects of this invention will be apparent from the disclosures in the specification and drawings.

The invention (in a preferred form) is illustrated in the drawings and hereinafter more fully described.

On the drawings:

Figure 1 is a side elevation of a novelty

toilet article embodying the principles of this invention.

Fig. 2 is a central vertical section thereof.

Fig. 3 is a top plan view of the article 60 with the cap removed.

Fig. 4 is a vertical central section of a modified form of the device.

As shown on the drawings:

The reference numeral 1, indicates a seated kewpie bathing girl or doll of hollow construction to afford a chamber 2, for holding face powder or other similar materials. The bottom or base 3, of the doll is provided with a filler opening adapted to be 70 closed by a removable cork or plug 4. The head 5, of the doll is provided with a plurality of dispensing apertures or openings 9, in the central portion of the top thereof to permit the powder contained within the 75 chamber 2, to be dispensed. Covering the top of the head 5, is a removable cloth cap 6, provided with a bow 7, or other ornamental trimming. Secured within the removable cap 6, is a lining 8, preferably 80 made of chamois skin, which may be used as a powdering shammy when the cap is removed and powder from the doll is sprinkled on said chamois lining.

Fig. 4 discloses a modified form of a 85 kewpie doll comprising a body 10, having a powder chamber 11, therein. The bottom 12, of the doll is provided with a filler opening which is closed by a removable cork or plug 13. The lower half of the head 14, is 90 integral with the body 10, and is closed by an integral top 15, provided with a plurality of apertures or openings 16. A circumferential groove is formed around the upper portion of the head 14, to permit the upper half 95 of the head or the skull 17, to be removably seated on the lower half of the head 14. The skull 17, is arched to afford a chamber or space 18, between the lower portion of the head 14 and the skull 17, to permit a powder 100 puff or chamois skin 19, to be seated on the apertured top 15, and beneath said skull when the same is in place.

The doll may be filled with face or talcum powder by removing the cork 4. Normally 105 the cloth cap 6, is engaged in place on the top of the head 5, to close the apertures 9. The article may be used as a toilet article and set on a dresser or dressing table to appear as an article of ornamentation. The 110 use of the device is self-evident. By removing the cap 6, and turning the same inside

out the chamois lining 8, may have powder from the chamber 2, sprinkled thereon. The chamois may then be used for powdering purposes, after which the cap is put back in 5 place.

The use of the modified form of the device shown in Fig. 4, is believed self-evident. The skull 17, may be painted to disclose a cap or hair as preferred.

10 It will, of course, be understood that the toilet articles disclosed are only preferred forms of the device and that dolls or statues of different designs may be constructed and used for the same purposes without interfering with the ornamental usefulness thereof. If preferred the device may be used as a condiment holder or for similar purposes.

15 I am aware that numerous details of construction may be varied through a wide range without departing from the principles of this invention, and I therefore do not purpose limiting the patent granted otherwise than necessitated by the prior art.

I claim as my invention:

- 20 25 1. The combination with a chambered doll having dispensing apertures therein, means to permit filling of said doll with powder, and means forming a part of the doll adapted to normally cover said apertures.
- 20 30 2. The combination with an apertured doll adapted to hold face powder, and means for normally covering said apertures adapted to be used as a powdering shammy.
- 35 3. The combination with a hollow kewpie doll for holding powder and having a filler

opening in the bottom thereof and dispensing apertures in the top of the head, and a removable powdering shammy adapted to normally cover said apertures.

4. The combination with a hollow kewpie 40 doll having dispensing apertures in the head thereof, said doll having an opening therein to permit powder to be inserted into the doll, removable means for closing said opening, a cloth cap removably engaged on the head of said doll to cover the dispensing apertures, and a chamois lining in said cap adapted to be used as a powdering shammy when the cap is removed.

5. The combination with a kewpie doll, of 50 a removable cap thereon adapted to be used as a powdering shammy.

6. The combination with an apertured hollow doll adapted to carry powder, of a cap removably placed on said doll, and a 55 lining in said cap adapted to be used as a powdering cloth when the cap is removed turned inside out and powder from the doll is sprinkled on the lining.

7. A toilet accessory comprising an apertured hollow doll adapted to carry face powder, and a removable cap for the doll adapted to be used as a powdering medium.

In testimony whereof I have hereunto subscribed my name in the presence of two 65 subscribing witnesses.

MAX COHN.
